(**) Term: **14 Years**

(57) **CLAIM**

(21) Appl. No.: **29/274,248**

The ornamental design for a ventilation interface, as shown and described.

(22) Filed: **Apr. 9, 2007**

Related U.S. Application Data

(63) Continuation of application No. 29/245,378, filed on Dec. 23, 2005.

DESCRIPTION

(51) **LOC (8) Cl.** **29-02**

FIG. 1 is a top and right front perspective view of a ventilation interface, showing our design;

(52) **U.S. Cl.** **D24/110.1; D24/110.4**

FIG. 2 is a right side view thereof;

(58) **Field of Classification Search** D24/110, D24/110.1, 110.4, 110.5, 164; 128/206.11, 128/206.27, 207.11, 207.13, 207.17, 207.18

FIG. 3 is a left side view thereof;

See application file for complete search history.

FIG. 4 is a front view thereof;

(56) **References Cited**

FIG. 5 is a rear view thereof;

U.S. PATENT DOCUMENTS

FIG. 6 is a top view thereof; and,

FIG. 7 is a bottom view thereof.
